UNITED STATES PATENT OFFICE.

HARRY FOTHERGILL, OF WESTMINSTER, LONDON, ENGLAND.

BOILER-FEED-WATER-SUPPLY SYSTEM.

Application filed November 2, 1922. Serial No. 593,591.

To all whom it may concern:

Be it known that I, HARRY FOTHERGILL, of Westminster, London, in the county of Middlesex, England, have invented certain new and useful Improvements in Boiler-Feed-Water-Supply Systems, of which the following is a specification.

This invention has reference to steam condensing and boiler feed water systems of the kind in which the condensate is removed from the condenser and delivered to the boilers by rotary pumps.

In systems of this kind it is desirable, in order to promote the satisfactory working of the feed pump, to maintain an approximately uniform pressure on the suction side of such pump, and the object of this invention is to provide means whereby this desideratum may be obtained under all conditions of working, particularly under varying conditions of load, such as when a ship is entering or leaving harbour.

For this purpose I provide means for automatically throttling or cutting off the delivery of the feed water on the discharge side of the feed pump whenever the pressure on the suction side of the feed pump falls below a predetermined limit. That is to say, when from any sudden change or fluctuation in load the pressure on the suction side of the feed pump falls, the delivery of water from such pump is throttled so as to immediately cause, on the suction side, a rise in pressure up to the desired normal, the throttling effect being removed as soon as the supply of water from the condensate pump is sufficient for, or greater than, the requirements of the feed pump and the pressure in its suction system rises. Means can be provided to admit a supplementary supply of water into the system immediately the load on the main engine is reduced, so that the throttling of the feed pump discharge is only of momentary duration and does not interfere with the supply of feed water to the boilers.

In the accompanying drawings the invention is diagrammatically illustrated Fig. 1 being a diagrammatic view illustrating the condensing plant of a steam turbine with my invention applied thereto.

Fig. 1^a is a detail of the valve indicated generally at 9 in Fig. 1.

Fig. 1^b is a detail of the valve indicated generally at 8 in Fig. 1.

Fig. 2 is an enlarged sectional view of a portion of the plant illustrated in Fig. 1, and,

Fig. 3 is a diagram of a modified arrangement.

In Fig. 1 C designates a main condenser from which the condensate is withdrawn by the extraction pump B which delivers through the auxiliary heater D into the suction pipe E of the feed pump 3, which delivers through a heater F to the boilers. Air is withdrawn from the condenser by the steam ejectors G and H, the latter discharging into the auxiliary heater D. J is the filter, K the feed tank and L the reserve feed tank which can be arranged in any convenient manner to suit the requirements of the system. In accordance with my invention this feed pump 3 delivers to the boilers through a throttle valve 1 connected on the delivery pipe 2 from the feed pump 3, and this throttle valve is operated by a piston or equivalent device 4 (Fig. 2) whose movement is controlled by the pressure in the suction system E of the feed pump. A convenient way of controlling this piston 4 is to provide it with a small hole or permanent leak 5 and subject it on one side to the pressure of the feed pump discharge 2, the escape of water from the other side—and thus the pressure—being regulated by a valve 6, such as a needle valve, operated by a spring in one direction and subjected to the pressure on the suction side E of the feed pump in the other direction. An automatic relief valve 8 for the escape of surplus water from the condensate pump into the feed tank or elsewhere as desired is provided in the feed pump suction pipe.

In order that the working of the apparatus may be understood, it is assumed that the loaded needle valve 6 closes when the pressure in the suction system E acting on the diaphragm 6^a rises above ten pounds per square inch, and the relief valve 8 opens upon the occurrence of a pressure of twelve pounds per square inch. When the system is working under normal conditions and the pressure on the suction side of the feed pump is maintained at between ten and twelve pounds, the valves do not operate and

the water supplied by the condensate pump is delivered direct to the boilers. When, however, there is a fall in pressure on the feed pump suction, such as may be caused by a sudden reduction in the speed of the main engines or turbines, the loaded needle valve 6 opens, relieving the pressure on the piston 4 operating the throttle valve 1, and thus causing such valve to begin to close and reduce the delivery from the feed pump. The pressure on the suction side E is therefore prevented from falling further, and when the supply of water from the condensate pump B increases, the action is reversed and the throttle valve 1 opens wider, if the supply of water from the condensate pump is greater than that required for boiler feeding purposes, the pressure on the suction side of the feed pump rises until at twelve pounds the surplus water passes through the relief valve 8 into the feed tank.

In order to ensure that a sufficient supply of water is available at all times to meet the boiler requirements, as for example when the condensate from the condenser is insufficient for boiler feeding purposes, an automatic by-pass valve 9 or other known means is provided to control a supplementary supply of water into the system.

Fig. 3 shows a modified arrangement wherein the throttle valve 1 is a duplex valve held in the closed position as shown in the drawings by a spring 10 when the pressure in the feed pump suction E is below a predetermined limit but immediately the pressure in the feed pump suction pipe rises this pressure action on the piston 11 operates to open the valve 1 so that the water discharge by the feed pump 3 passes to the boilers. A relief valve 8 is provided as before in the feed pump suction pipe also a by-pass valve 9 controlled by the pressure in the turbine 20 and through which valve water can pass from a tank to the condenser C.

In the arrangements illustrated the by-pass valve 9 is similar to that described in Patent No. 1,392,003 and is operated by the pressure in the main turbine or engine, so that when the load on the main turbine or engine falls below a predetermined amount the valve opens and admits water from the feed or reserve tank into the condenser. Thus, coincident with a reduction in load, there is a supplement of water which maintains the supply of water for the boilers, and, if not required for the boilers, the surplus passes through the relief valve back into the tank.

It will be understood that the apparatus herein described may be constructed in any convenient form provided it will allow of the working above described. For example, when the throttle valve is of the balanced type, another piston may be provided for opening it. Also, the throttle valve with

its operating piston or pistons may be placed in the same casing, or if desired the throttle and operating piston or pistons may be separate and connected together by suitable mechanism.

70

What I claim and desire to secure by Letters Patent is:—

1. A steam condensing and boiler feed water system comprising a condenser, a boiler feed pump to which condensate from the condenser flows, and an automatically operating throttle valve arranged in the system on the discharge side of the feed pump, said throttle valve operating automatically to throttle the supply of water from the feed pump to the boilers if and when the pressure on the suction side of the feed pump falls below a predetermined value and to remove said throttling effect if and when said pressure rises again, whereby a substantially uniform pressure is maintained on the suction side of said feed pump. 75

2. A steam condensing and boiler feed water system comprising a condenser, a boiler feed pump to which condensate from the condenser flows, a throttle valve arranged in the system on the discharge side of the feed pump and adapted to operate automatically to throttle the supply of water from the feed pump to the boilers when the pressure on the suction side of the feed pump falls below a predetermined value and to remove said throttling effect when said pressure rises again, and a by-pass valve interposed in a connection between a supply tank and the feed system, said valve operating automatically to by-pass water from the tank to the system whenever the main engine falls below a predetermined proportion of its full normal load whereby, by the operation of said throttle valve, a substantially uniform pressure is maintained on the suction side of said feed pump and by the operation of the by-pass valve a sufficient supply of water for the boilers is at all times ensured. 95

3. A steam condensing and boiler feed water system comprising a condenser, a boiler feed pump to which condensate from the condenser flows, a throttle valve arranged in the system on the discharge side of the feed pump and adapted to operate automatically to throttle the supply of water from the feed pump to the boilers when the pressure on the suction side of the feed pump falls below a predetermined value and to remove said throttling effect when said pressure rises again, a tank, a connection between the tank and the feed system, and an automatic relief valve in said connection operating to permit the passage of any excess water in the system to said tank. 115

4. A steam condensing and boiler feed water system comprising a condenser, a boiler feed pump to which condensate from

130

the condenser flows, a throttle valve arranged in the system on the discharge side of the feed pump and adapted to operate automatically to throttle the supply of water from the feed pump to the boilers when the pressure on the suction side of the feed pump falls below a predetermined value and to remove said throttling effect when said pressure rises again, a tank, a connection between the tank and the feed system, and an automatic relief valve in said connection operating to permit the passage of any excess water in the system to said tank, and a by-pass valve interposed in a connection between a supply tank and the feed system, said valve operating automatically to bypass water from the tank to the system whenever the main engine falls below a predetermined proportion of its full normal load whereby, by the operation of said throttle valve, a substantially uniform pressure is maintained on the suction side of said feed pump, and by the operation of the by-pass valve a sufficient supply of water for the boilers is at all times ensured.

5. A steam condensing and boiler feed water system comprising a condenser, a boiler feed pump to which condensate from the condenser flows and an automatically operating throttle valve having a piston whose movement is controlled by the pressure on the suction side of the feed pump arranged in the system on the discharge side of the feed pump, said throttle valve operating automatically to throttle the supply of water from the feed pump to the boilers if and when the pressure on the suction side of the feed pump falls below a predetermined value and to remove said throttling effect if and when said pressure rises again whereby a substantially uniform pressure is maintained on the suction side of said feed pump.

6. A steam condensing and boiler feed

water system comprising a condenser, a boiler feed pump to which condensate from the condenser flows and an automatically operating throttle valve having a piston whose movement is controlled by the pressure on the suction side of the feed pump said piston being subject to the delivery pressure of the feed pump on one side, a permanent leak provided in said piston, and a valve permanently loaded in one direction and subject to the pressure on the suction side of the feed pump in the other direction through which water leaking through the piston from the feed system is permitted to escape, the throttle valve being arranged in the system on the discharge side of the feed pump, said throttle valve operating automatically to throttle the supply of water from the feed pump to the boilers if and when the pressure on the suction side of the feed pump falls below a predetermined value and to remove said throttling effect if and when said pressure rises again whereby a substantially uniform pressure is maintained on the suction side of said feed pump.

7. A steam condensing and boiler feed water system comprising a condenser, a pump for withdrawing condensate from the condenser, a boiler feed pump to which condensate from the condenser flows and an automatically operating throttle valve arranged in the system on the discharge side of the feed pump, said throttle valve operating automatically to throttle the supply of water from the feed pump to the boilers if and when the pressure on the suction side of the feed pump falls below a predetermined value and to remove said throttling effect if and when said pressure rises again whereby a substantially uniform pressure is maintained on the suction side of said feed pump.

In testimony whereof, I affix my signature.
HARRY FOTHERGILL.
